UNITED STATES PATENT OFFICE.

WALTER MYERS, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

EMBROIDERING MACHINE.

Application filed March 24, 1923. Serial No. 627,249.

To all whom it may concern:

Be it known that I, WALTER MYERS, a citizen of the United States, residing at Bridgeport, in the county of Fairfield and State of Connecticut, have invented certain new and useful Improvements in Embroidering Machines, of which the following is a specification, reference being had therein to the accompanying drawings.

10 This invention relates to improvements in embroidering machines and more particularly in the universal feed embroidering machines of the so-called Bonnaz type wherein a covering thread or cord is wound around 15 the sewing thread or around the sewing thread and a filler cord or braid.

One of the objects of this invention is to provide improved means for varying the spacing of the convolutions of the covering 20 thread or cord wound about the sewing thread or filler cord or both.

The invention has for another object to provide improved means in a universal feed 25 embroidering machine for rendering the covering thread or cord winding device operative or inoperative, at the will of the operator, without requiring a re-timing of the covering-thread guide with respect to the stitch-forming mechanism.

30 Other objects of the invention will be apparent from the following description and claims.

To attain the objects of the present invention, the present improvement has been embodied in a universal feed embroidering machine in which a covering thread spool and guide are supported upon the machine frame for bodily rotation coaxially of the needle-bar. Loosely mounted upon the main-shaft 35

40 of the machine and selectively keyed thereto at the will of the operator is a series of different size driving gears in constant mesh with an intermediate step-gear comprising a series of gears secured against relative rotation housed within the overhanging bracket-arm and constantly in driving engagement with a driven gear, loosely journaled upon the feed-direction determining shaft 45

50 and forming part of the usual differential gearing for rotating the covering-thread guide. The driving gear requisite to impart the desired speed of rotation to the covering-thread guide may be selectively secured to the main-shaft of the machine by

means of a key slidingly mounted in a slot 55 of said shaft and suitably connected with a manually manipulated lever. This lever may be secured to position the sliding key in gear-engaging and disengaging positions and as the several gears remain constantly in mesh the covering-thread guide may be readily thrown into and out of operation at will and the spacing of the convolutions of the covering-thread may be readily varied 60 without destroying the timing or the position of the covering-thread guide with respect to the stitch-forming mechanism.

In the accompanying drawings, Fig. 1 is a front side elevation, partly in section, of a universal feed embroidering machine in 70 which a preferred form of the present improvement has been embodied. Fig. 2 is a detail of a portion of the bracket-arm of the machine illustrating the key-sliding lever. Fig. 3 is an enlarged horizontal section of a 75 portion of the machine bracket-arm. Fig. 4 is an enlarged vertical section of the main and feed-direction-determining shafts. Fig. 5 is a detail view illustrating the relationship of the covering-thread guide controlling driving and driven gears.

Referring to the drawings, the embroidering machine is constructed with a bed-plate 1, from which rises the vertical standard 2 of the overhanging bracket-arm 3 terminating in the head 4, to which is suitably secured the needle-bar and feed-supporting frame 5. Journaled in suitable bearings provided in the overhanging arm is the main or driving shaft 6. The frame 5 is formed 85 with parallel, horizontally extending bearing brackets 7 and 8, having vertically aligned apertures in which the cylinder 9 is journaled for rotary movements.

Mounted in the cylinder 9 is the needle-bar 10, vertically reciprocated from the main-shaft 6 and constrained to rotate with the cylinder 9 in the usual manner. At its lower end the needle-bar carries the hook-needle 11 adapted to coact in a well known 90 manner with a chain-stitch looper (not shown), to enchain loops of thread above the throat-plate 12, the thread being supplied from a spool carried by the spool-pin 13 located below the bed-plate 1. While a chain-stitch mechanism is embodied in the machine being described, it will be evident 100 that the covering-thread device controlling 105

mechanism is equally adapted for embodiment in a lock-stitch machine, such for instance as is disclosed in my U. S. Patent No. 1,325,033, dated Dec. 16, 1919.

- 5 The feeding mechanism comprises a feeding foot 14 which is actuated to feed the work in a direction corresponding, as usual, to the direction of rotation of the cylinder 9. To effect rotation of the cylinder 9 under 10 manual control there may be employed the usual connections such as disclosed in my Patent No. 1,325,033. These connections comprise in part a bevel gear 15, fixed upon the cylinder 9 and meshing with a similar 15 gear 16 upon a stud-shaft 17 fixed upon the frame 5. Mounted upon the stud-shaft 17 to rotate with the bevel-gear 16 is a pinion 18 meshing with a spur-gear 19 fixed upon the forward end of the feed-direction determining 20 shaft 20 journaled in the overhanging bracket-arm of the machine. The shaft 20, as is usual in machines of this class, has gear and shaft connections with a hand-crank 21 disposed below the bed-plate 1, 25 whereupon by manipulation of said hand-crank the shaft 20 may be rotated in opposite directions to change the direction of work-feeding movement of the feeding-foot 14.
- 30 During the sewing operation the hook-needle 11 is reciprocated through the tubular nipple 22, which as usual rotates with the cylinder 9 but is vertically reciprocated thereupon and may be designed to function 35 either as a needle-stripper or as a combined braid-guide and needle-stripper as is well known.

Loosely journaled upon the machine frame between the bracket 8 and a collar 23 40 fixed upon the frame is a spool-carrier sleeve 24 upon which is secured the covering-thread spool-carrier 25 and the covering-thread guide 26 having the usual thread guiding aperture adjacent the needle. The guide 26 45 is bodily rotated about an axis constituting the path of reciprocation of the needle to wind the covering-thread about the sewing thread or about the sewing thread and a filler braid or cord dependent upon the character 50 of the work desired. While in the present instance the covering-thread spool-carrier 25 is also bodily rotated, this carrier may be otherwise supported as for instance by mounting the covering-thread spool so 55 that its unwinding axis is concentric with the needle-bar, as is well known.

In order to rotate the guide 26 and the covering-thread spool-carrier 25, the sleeve 24 fixedly carries a spur-gear 27 in mesh 60 with an intermediate pinion 28 supported by a stud-screw 29 threaded into the frame 5. The pinion 28 is in constant engagement with a spur-gear 30 secured upon the lower end of a vertical shaft 31 suitably journaled 65 in the machine frame. The gears 27, 28

and 30 are preferably enclosed by a housing 32 detachably secured upon the machine frame. At its upper end, the vertical shaft 31 carries a bevel gear 33 meshing with a similar gear 34 upon the forward end of a sleeve 35, journaled in a web 36 in the overhanging bracket-arm of the machine and sleeved upon the feed-direction-determining shaft 20. Upon the other side of the web 36, there is secured upon the sleeve 35 a 70 bevel-gear 37 forming part of a differential gear mechanism which in principle is well known in this class of machines. Meshing with the bevel-gear 37 is an intermediate pinion 38 journaled upon the reduced upper 80 end of a gear-bracket 39 and held in position thereupon by means of a cap-screw 40. The gear-bracket 39 is apertured for reception of the shaft 20 upon which it is secured against relative rotation by means of 85 the set-screw 41. The pinion 38 is also in constant mesh with a bevel-gear 42 upon one end of a sleeve 43, loosely journaled upon the shaft 20 and held against endwise movement thereupon by means of a collar 44. A spur-gear 45 is disposed upon the sleeve 43 to rotate therewith and is rotated from the main-shaft 6 by mechanism under manual control for varying the speed of rotation of the gear 45 and therefore the spacing 90 of the convolutions of the covering thread.

Loosely journaled upon the main-shaft 6 and held against endwise movement thereupon by means of collars, as 46, is a series 100 of driving gears 47, 48, 49 and 50 of successively decreasing diameters and separated by washers, as 51. Each of these gears is provided with a key-slot as 52 adapted to be successively engaged by the beveled nose 53 on the forward end of a key 54 slidingly disposed in a way 55 provided in the main-shaft 6. At its opposite end the key 54 is formed with a notch 56 loosely entered by the unthreaded reduced end of a screw 57 threaded into a grooved collar 58 also slidingly disposed upon the shaft 6. The collar 58 is engaged by a stud 59 upon the upper end of a crank-arm 60 having a fulcrum-pin 61 journaled upon a detachable front-plate 62 secured upon the overhanging bracket-arm of the machine by means of a screw 63. Rigidly secured upon the fulcrum-pin 61, so as to in effect comprise a bellcrank-lever in connection with the crank-arm 60, is a manually manipulated arm 64 having at its outer end an apertured boss 65 in which is slidingly mounted a locking-pin 66. Threaded upon the outer end of the pin 66 is a nut 67 while its inner end may be yieldingly seated under the action of a spring 68, in any one of a plurality of apertures 69 formed in the front-plate 62. It will be apparent that by shifting the locking-pin 66 into the proper aperture 69, the key 54 will be slidingly displaced in the way 110 115 120 125 130

55, whereupon the beveled nose 53 of the key is constrained to enter the key-slot 52 of the selected driving gear under the action of a spring 70 interposed between the key and the base of the way 55. As the key 54 is shifted from one gear-engaging position to another, the washers 51 depress the nose 53 out of engagement with the gear last secured to the shaft to serve as a safeguard against simultaneously securing two gears to the shaft 6 and also to afford a rest for the key in gear disengaging position. Depressions, as 71, are provided in the front-plate 62 to alternate with the apertures 69 and when the locking pin 66 is seated in any one of the depressions 71, the key 54 is disengaged from the driving gears, the nose 53 contacting one of the washers 51.

Preferably secured upon the rear side of the overhanging bracket-arm 3 is a gear-housing 72 in which is suitably journaled a counter-shaft 73. Fixed upon the counter-shaft 73 is an intermediate step-gear comprising a series of four-gears 74, 75, 76 and 77 of successively increasing diameters and secured together by means of screw-bolts, as 78. The intermediate gears 74, 75, 76 and 77 are in constant mesh with the driving gears 47, 48, 49 and 50, respectively, while the gear 74 which has a relatively wide face is also in mesh with the spur-gear 45 upon the shaft 20. Inasmuch as the driving gears can be keyed to the main-shaft only when the beveled nose 53 of the key is in alinement with the key-slots 52 of said gears and furthermore as the driving and intermediate gears, together with the spur-gears 45 are in constant mesh, the relative timing thereof with respect to the stitch-forming mechanism can not be destroyed by rendering the driving gears ineffective by manual manipulation of the arm 64.

In the operation of the stitching mechanism, when any one of the driving gears is keyed to the main-shaft 6, the covering-thread guide 26 is positively rotated, through the gear connections described, about the needle to wind the covering-thread about the needle-thread or the needle-thread and a filler cord or braid, the number of convolutions of the covering-thread with respect to the number of stitches being dependent upon the driving gear selected, as will be evident. The gears in the present machine are preferably of such a ratio that, when the gear 47 is keyed to the main-shaft, the covering thread-guide 26 makes one complete revolution during the formation of each stitch, while the driving-gears 48, 49 and 50 each successively require one additional stitch to complete one revolution of the covering-thread-guide. The present construction therefore comprises conveniently positioned means, operable at the will of the operator, for both changing the spacing of

the convolutions of the covering thread and for rendering the covering-thread guide inoperative without requiring retiming of the guide.

Having thus set forth the nature of the invention, what I claim herein is:—

1. In an embroidering machine, in combination, a main-shaft, stitch-forming mechanism including a reciprocatory needle, universal feeding mechanism, mechanism for controlling the direction of feed, a covering-thread guide disposed to rotate about said needle, actuating mechanism operatively connected with said main-shaft for rotating said guide, and means independent of the direction of feed for at will varying the relative speed of rotation of said main-shaft and said guide during the operation of the machine.

2. In an embroidering machine, in combination, stitch-forming mechanism including a reciprocatory needle, means for reciprocating said needle, universal feeding mechanism, mechanism for controlling the direction of feed, a covering-thread guide disposed to rotate about said needle, actuating mechanism for rotating said guide, and means independent of the direction of feed for at will varying the relative timing between said reciprocating needle and the rotating thread-guide during the operation of the machine.

3. In an embroidering machine, in combination, stitch-forming mechanism including a reciprocatory needle, means for reciprocating said needle, universal feeding mechanism, mechanism for controlling the direction of feed, a covering-thread guide disposed to rotate about said needle, and actuating mechanism for rotating said guide including a series of driving gears, a series of driven gears constantly in mesh with said driving gears, and shiftable means for driving the driven gears from any one of said driving gears.

4. In an embroidering machine, in combination, stitch-forming mechanism including a reciprocatory needle, means for reciprocating said needle, universal feeding mechanism, mechanism for controlling the direction of feed, a covering-thread guide disposed to rotate about said needle, and actuating mechanism for rotating said guide including a series of driving gears, a series of driven gears constantly in mesh with said driving gears, and shiftable means for at will rendering an intermeshing driving and driven gear of said series effective or ineffective to rotate said covering-thread guide.

5. In an embroidering machine, in combination, stitch-forming mechanism including a reciprocatory needle, a covering-thread guide disposed to rotate about said needle, a driving shaft, a series of driving gears upon said driving shaft, a counter-shaft, a series

of intermediate gears carried by said counter-shaft in constant mesh with said driving gears, means for selectively driving an intermeshing driving and intermediate gear of said series, and operative connections between the driven intermediate gear and said guide to rotate the latter.

6. In an embroidering machine, in combination, stitch-forming mechanism including 10 a reciprocatory needle, a covering-thread guide disposed to rotate about said needle, a driving shaft, a series of driving gears upon said driving shaft, a counter-shaft, a step-gear carried by said counter-shaft comprising 15 a series of intermediate gears secured to rotate together and disposed in constant mesh with said driving gears, means for selectively securing a driving gear to said driving shaft, and operative connections between 20 the step-gear and said guide to rotate the latter.

7. In an embroidering machine, in combination, stitch-forming mechanism including a reciprocatory needle, a covering-thread 25 guide disposed to rotate about said needle, a driving shaft, a series of driving gears upon said driving shaft, a counter-shaft, a series of intermediate gears carried by said counter-shaft in constant mesh with said driving 30 gears, means for selectively driving an intermediate gear from one of said driving gears, operative connections between the driven intermediate gear and said guide to rotate the latter, and means for at will ren-

dering the driving gears ineffective to rotate 35 the guide.

8. In an embroidering machine, in combination, stitch-forming mechanism including a reciprocatory needle, a covering-thread guide disposed to rotate about said needle, a 40 driving shaft, a series of driving gears upon said shaft, a driven shaft, a series of driven gears upon said driven shaft in constant mesh with said driving gears, operative connections between said driven gears and said 45 guide for rotating the latter, and means for selectively securing any gear of one of said series to its shaft including a sliding key, a lever and means for maintaining said lever with the sliding key in gear-engaging position. 50

9. In an embroidering machine, the combination with stitch-forming mechanism including a reciprocatory needle, means for reciprocating said needle, and a covering-thread guide disposed to rotate about said needle, of means for at will rotating said 55 guide at different speeds with respect to the reciprocations of said needle, said means including a device for selectively determining 60 the speed of rotation of said guide while maintaining a predetermined position thereof with respect to said needle at a given point in the stitch-forming cycle.

In testimony whereof, I have signed my 65 name to this specification.

WALTER MYERS.
